TIME CONTROLLED SWITCH MECHANISM

Reuben W. Lovering, Minneapolis, Minn.

Application December 30, 1943, Serial No. 516,163

1 Claim. (Cl. 200—39)

1

My invention relates to time controlled switch mechanisms and has for an object to provide a time controlled switch mechanism, the operation of which can be readily reversed.

An object of the invention resides in providing a time controlled switch mechanism which can be made to either open a circuit at a predetermined time or which can be made to close a circuit at a predetermined time.

Another object of the invention resides in providing a time controlled switch mechanism which will function when set in operation to maintain a circuit closed for a predetermined length of time and then open the circuit, or which can be reversed in operation to maintain the circuit open for a predetermined length of time and then close the circuit.

A still further object of the invention resides in providing a mounting movable in opposite directions and in supporting a switch thereon in a manner to cause opening and closing of the switch upon movement of the mounting in opposite directions.

A feature of the invention resides in providing a switch mechanism of such character in which the switch may be reversed in position upon the mounting to cause reversal in operation of the switch upon movement of the mounting.

Another object of the invention resides in pivotally supporting the switch upon the mounting to permit of end to end movement of the switch to procure reversal in operation of the switch.

A still further object of the invention resides in utilizing a mercury switch attached to a swingable support adapted to be moved to tilt the switch from open to closed position and vice versa and in further supporting the switch on the mounting in such a manner that the switch may be turned end for end so as to procure reversal in operation of the switch.

Another object of the invention resides in pivotally supporting the switch on the mounting for movement through an angle of 180°, so as to procure end for end movement of the switch, whereby reversal in operation of the switch is procured.

Other objects of the invention reside in the novel combination and arrangement of parts and in the details of construction hereinafter illustrated and/or described.

In the drawings:

Fig. 1 is an elevational view of a clock with a switch mechanism illustrating an embodiment of my invention applied thereto and showing a portion of the case of the clock broken away.

2

Fig. 2 is a view similar to Fig. 1, showing the switch in reversed position.

Fig. 3 is an end elevational view of the structure shown in Fig. 1, with portions of the case removed to illustrate the construction of the switch and supporting structure therefor.

Fig. 4 is a fragmentary plan view of the structure shown in Fig. 1 with portions of the case and other parts cut away to illustrate the control device for the switch and drawn to an enlarged scale.

Fig. 5 is a view similar to Fig. 1 of a modification of the invention.

Fig. 6 is a fragmentary view similar to Fig. 3 of the structure shown in Fig. 5.

In the operation of radios and other electrical appliances, it becomes desirable at times to turn on the appliances at a predetermined time, as for example, to turn on the heat under a cooking utensil or to turn on the radio at the time scheduled for a certain program. At other times, it becomes desirable to turn off an electric circuit at a desired time. In the cooking of certain foods, it may be desirable to cook the same for a certain length of time and then turn off the current. Likewise, it may become desirable to turn off the radio at the end of a certain program. The instant invention provides a time controlled switch mechanism which may be readily applied to a clock and means by which either of these functions can be readily procured by the simple and rapid manipulation of the proper control elements thereof.

For the purpose of illustrating the application of my invention, I have shown in the drawings an ordinary clock 10 in the nature of an alarm clock which may be electrically operated or spring operated, as desired. Inasmuch as the invention does not consist in the construction of the clock, the same has not been shown in detail, though it can be readily comprehended that any suitable clock mechanism such as are now well known in the art, may be used for the purpose. The clock 10 shown comprises a case 11 having a front wall 12, a rear wall 13 and end walls 14 and 15 connected together by a curved upper wall 16. The case 11 is supported on a base 9. Within the case is disposed a clock mechanism indicated in its entirety by the reference character 17, best illustrated in Figs. 1 and 3. This clock mechanism comprises a front frame 27 and a rear frame 28 held in spaced relation by means of posts 29 in the customary manner. The said clock mechanism includes an hour hand sleeve 18 and a minute hand arbor 19 concentrically

mounted for rotation carrying the usual minute hand 21 and the hour hand 22, both movable over a dial 23 formed on the front wall 12 of case 11 and which serves as the face of the clock. These hands are driven by the usual clock gear train which is not shown in the drawings.

The clock mechanism 17 further includes an arbor 24 which is similar to the arbor of an alarm clock used for timing the operation of the alarm. This arbor is journaled in the frames 27 and 28 of the clock mechanism 17 and protrudes outwardly from the rear wall 13 of the case 11, being provided with a knob 31 by means of which the same may be rotated. A suitable friction mechanism, not shown, mounted on arbor 24, holds the same in position when manually set. Mounted on the end of the arbor 24 is a hub 25 which has attached to it a finger 26 extending outwardly therefrom. This finger is adapted to engage a barrel cam 32 slidably mounted on the arbor 24 and attached to a gear 33. The gear 33 is driven from a pinion 34 which is mounted on an arbor 35 driven from the gear train of the clockwork 17. The cam 32 has an elevated cam surface 35 formed with a notch 36 therein. The cam 32 is held in engagement with the finger 26 by means of a leaf spring 37 which is attached to the frame 27 by means of a rivet 38. This leaf spring is flexed so as to urge the cam 32 toward the finger 26 and is provided at its end with a lug 39 which projects through a suitable opening 41 in the frame 27 and extends into the space between the two frames 27 and 28. The pinion 34 is of such length that the gear 33 may slide axially relative to the same and cause the said gear to remain at all times in mesh with the teeth of said pinion. When the cam 32 is rotated, and the finger 26 reaches the notch 36, said cam slides axially on arbor 24 through the action of the spring 37 and lug 39 is rapidly moved in a direction towards the face of the clock. The time at which such action takes place is controlled by the position of the arbor 24 which is provided at its outer end with a hand 42 movable with reference to a dial 43, formed on the front wall 12 of the clock.

The form of the invention shown in Fig. 1 comprises a mounting indicated in its entirety by the reference numeral 44. This mounting consists of an arm 46 which is brazed or otherwise secured to an arbor 47. The arbor 47 is journaled in the frames 27 and 28. A boss 48 extends upwardly from the arm 46 at the locality of the arbor 47 and is threaded to receive a screw 49. The screw 49 passes through the base of a U-shaped spring clip 51 which is rotatably mounted on said screw and which is frictionally held in position thereby.

The clip 51 receives and supports a mercury switch 50. This switch includes a tube 52 of glass or other suitable insulating material having contacts 53 and 54 at one end and a globule of mercury 55 movable from one end of the tube to the other. When the switch 50 is tilted to the position shown in full lines in Fig. 1, the mercury 55 flows away from the contacts 53 and 54 and opens the switch. When the switch is tilted to the position shown in dotted lines in Fig. 1, the mercury bridges across the contacts 53 and 54 and closes the switch.

Attached to the under side of the arm 46 is a depending member 56 which has a projection 57 extending angularly therefrom and adapted to rest upon the lug 39 of spring 37 when the same is in its innermost position. The lug 39 and spring 37 serve as a latching means which oper-

ates to hold the arm 46 in the position shown in full lines in Fig. 1. A weight 60, attached to the end of the arm 46, tends to move said arm to its dotted-line position shown in Fig. 1 in which the switch 50 is in its corresponding dotted-line position and closed. It will be readily comprehended that as the gear 33 rotates, the finger 26 passes along the surface 35 of cam 32 and finally enters the notch 36. When this occurs, lug 39 is withdrawn from engagement with the projection 57 and the arm 46 operated through action of the weight 60 moves the switch from the one position to the other.

The switch 50 may be rotated about the axis of the screw 49 by means of a shaft 58 having a thumb piece 59 secured to the end of the same. This shaft is attached to a U-shaped spring clip 61 similar to the clip 51 which extends over the clip 51 and operates in unison therewith. The shaft 58 extends through a slot 62 in the upper wall 16 of case 11 and moves along this slot from one extreme position to the other as shown in Fig. 1. The clip 51 carrying the switch 50 may be rotated by means of shaft 58 and the thumb piece 59 from the position shown in Fig. 1 to that shown in Fig. 2. When at the latter position, the tube 52 is turned end for end and the operation of the switch is reversed. When the parts are disposed as shown in full lines in Fig. 1, the switch 50 is open. When the parts are arranged as shown in full lines in Fig. 2, the switch is closed. When the parts are moved to the position shown in dotted lines in Fig. 1, the switch is closed and when moved to the position shown in dotted lines in Fig. 2, the switch is open. Thus, it will become readily comprehended that the switch may be moved so as to procure reversal in operation thereof by rotating the same through an angle of 180° about the axis of the screw 49.

To limit movement of the switch 50, a pin 63 is provided on the under side of the clip 51. This pin is adapted to engage either of two lugs 64 projecting outwardly from the hub 48. When the switch is turned to either position, the pin 63 limits the movement of the switch to either of its operating positions. The disposition of the switch 50 can be indicated by constructing the thumb piece 59 in the form of an arrow, as shown in Figs. 1 and 2, and by placing upon the upper wall 16 of the case suitable characters indicating the function of the switch when the thumb piece 59 points in either direction.

The switch 50, after having been released by the clock mechanism, must be manually reset. For this purpose, the thumb piece 59 and the shaft 58 are employed. Resetting occurs when the said shaft and thumb piece are moved from the dotted-line positions shown in Figs. 1 and 2 to the full-line positions shown in said figures. Inasmuch as such movement of the arm 46 occurs when the lug 39 is in its innermost position, a cam surface 66 is formed on the depending member 56 which engages the lug 39 and forces the spring 37 outwardly, while the member 56 is clearing said lug. By means of this construction, the switch can be reset after the finger 26 rides upon the outer surface 35 of the cam 32. As soon as the cam 66 passes the lug 39, the said lug springs back and release of the thumb piece 59 causes the weight 60 to again bring the projection 57 to rest upon the lug 39.

The operation of the invention is as follows:

The contacts 53 and 54 are connected through suitable flexible leads 68 with the circuit with 75 which the switch is to be used. This may be ac-

complished by means of suitable plugs, not shown, or in any other desirable manner. If the circuit is to be turned on at a particular time, the thumb piece 59 is turned in the direction shown in Fig. 1 and the shaft 58 moved toward the right, as shown in that figure, until the projection 57 rests upon the lug 39 of spring 37. The arbor 24 is now turned through the knob 31 until the pointer 42 comes opposite the desired time of day noted on the dial 43, at which the switch is to be operated. When this time arrives, finger 26 on arbor 24 enters into notch 36 in cam 32 and the said cam, through the action of spring 37, is moved axially along arbor 24 toward the face or front wall 12 of the case 11 of the clock. This allows the lug 39 on spring 37 to be withdrawn from engagement with the projection 57 and arm 46 through the action of weight 60 drops, swinging the mounting 44 to the left and tilting the switch 58 until the mercury 55 in tube 52 reaches the contacts 53 and 54 and bridges across the same. The circuit is now completed and the radio or other appliance to be actuated is energized. If it is desired to turn off the radio or other appliance at a particular time, the thumb piece 59 is turned toward the left, as shown in Fig. 2 and the same procedure adopted. The degree of rotation of mounting 44 is limited by the pin 63 when the same engages the lugs 64.

In Figs. 5 and 6, I have shown a modification of the invention. In this form of the invention, the clock and actuating mechanism for the arbor supporting the switch is the same as that shown in the other form of the invention and the description thereof will not be repeated. The corresponding parts in this form of the invention are indicated by the same reference numerals as used for the parts of the form of the invention previously described, except that the digit 1 has been prefixed to such reference numbers.

In the form of the invention shown in Figs. 5 and 6, the arbor 147 is journaled in the frames 127 and 128, but has an extension 171 which projects through the rear wall 113 of case 111. On this extension is rotatably mounted a sleeve 172 which has a flange 173 attached thereto and projecting outwardly therefrom. Mounted on the extension 171 adjacent the frame 128 is a hub 174 which is provided with a spring disk 175 adapted to bear against the flange 173. By means of this construction, friction is afforded between the sleeve 172 and the extension 171, whereby said sleeve is supported in rotatably adjusted position relative to the arbor 147. A nut 176, screwed upon the end of the extension 171, engages the end of the sleeve 172 and urges the flange 173 into engagement with the disk 175. A knob 177 is secured to the protruding end of the sleeve 172 by means of a set screw 178 and serves to rotate the sleeve 172. This knob has a pointer 179 on it by means of which the position of the parts carried by the sleeve will be known from the exterior of the clock. The movement of the sleeve 172 is limited by means of a lug 181 extending outwardly from flange 173 which is adapted to engage either of two ears 182 formed on the disk 175.

The mounting 144 for the tube 150 is identical with that shown in Fig. 1, excepting that clip 61

is omitted. This mounting is directly attached to the sleeve 172 by soldering or otherwise, as indicated at 183. When the sleeve 172 is rotated, switch 150 can be moved from the full-line position shown in Fig. 5 to the dotted-line position in which the tube is moved end for end. Thus, it will become apparent that the switch may be arranged to either open or close upon release by the clock mechanism. It will be noted that the switch 150 is disposed exteriorly of the frame 128. To accommodate this arrangement of parts, the case 111 is made slightly wider than the case 11 shown in Figs. 1 to 4, inclusive.

For resetting the switch mechanism, a lever 184 is employed which is attached to the arm 146 at the locality of the arbor 147. This lever projects upwardly through a slot 162 in the upper wall 116 of case 111 and is provided with a knob 159 by means of which the same may be manipulated. This lever and knob serve the same purpose as the shaft 58 and thumb piece 59 of the other form of the invention.

The operation of the form of the invention shown in Figs. 5 and 6 is similar to that previously described. Reversal of operation of the switch mechanism is procured through rotation of the knob 177 by changing the position of the switch 150 from its full-line position shown in Fig. 5 to its dotted-line position shown in the same figure. The back 113 of case 111 is provided with suitable legend indicating the operation of the switch, so that the operator may know by the position of the pointer 179 whether or not the switch is arranged for opening or closing action upon release by the clockwork.

The advantages of my invention are manifest. The device is extremely simple and can be constructed at a nominal expense. By the use of a mercury switch, the mechanism will operate continuously without interruption or failure. The same mechanism will serve to either open or close the circuit as the operator desires. Suitable legend marked on the case of the clock indicates whether the device is set for opening or closing of the circuit. The switch mechanism can be reset at any time after the clock has run for a suitable length of time beyond the time of the release position.

Changes in the specific form of my invention, as herein described, may be made within the scope of what is claimed without departing from the spirit of my invention.

Having described my invention, what I claim as new and desire to protect by Letters Patent is:

In a time controlled switch mechanism, a mounting, means for pivoting said mounting for movement in opposite directions about a horizontal axis, a switch carried by the mounting and disposed above the axis thereof and extending in a substantially horizontal direction, said switch opening upon movement of the mounting in one direction and closing upon movement of the mounting in the other direction and means for changing the position of said switch from above the axis to a position below the axis to move the switch end for end to reverse the operation of the switch and time controlled means for controlling the movement of the mounting.
